SUCTION CLEANER

Frank L. Pierce, Garden City, N. Y., assignor to
The Hoover Company, North Canton, Ohio, a
corporation of Ohio

Application December 29, 1939, Serial No. 311,491

4 Claims. (Cl. 15—16)

This invention relates to improvements in suction cleaners and more particularly to an improved design for suction cleaners, wherein the operative and purely utilitarian parts of the cleaner are assembled as a completely operative device, although lacking a finished appearance, this being provided by an over-all appearance housing or cover preferably lined throughout its inner surface with a sound-absorbing material.

Hence, the object of the invention is to provide a cleaner design which will permit the structural elements to be assembled in accordance with the best engineering practice and then conceal the otherwise substantially completed cleaner within a light ornamental housing serving primarily to enhance the appearance of the cleaner and secondarily, as a sound-deadening enclosure calculated to substantially reduce the ordinary operating noises.

A preferred embodiment of this novel cleaner design has been disclosed in the accompanying drawings, in which:

Figure 1 is a general view of the cleaner in side elevation for the most part, but with the outer appearance housing in vertical section;

Figure 2 is a perspective view of the cleaner as viewed from above, with a section of the dome-like motor housing removed to show the arrangement beneath; and

Figure 3 is a perspective view following somewhat that of Figure 2 but with the appearance housing displaced immediately above the main body of the cleaner.

Apart from the particular arrangement of the various parts and elements that make up the cleaner, the one herein disclosed is typical of any standard portable suction cleaner and consists generally of a suction-creating unit including a fan chamber 1, a motor 2 superimposed upon said fan chamber and having direct driving connection with the fan 1a mounted within said fan chamber and a nozzle 3 consisting of a transversely elongated casing extending across the front of the fan chamber and having the usual downwardly opening suction mouth. The chamber formed by the nozzle casing 3 communicates with the fan chamber through a rearwardly extending passage 4 communicating with an inlet opening in the bottom wall of the fan chamber 1 and formed in part by a removable bottom plate 4a.

The fan chamber 1, generally circular in shape, is extended rearwardly in the form of an exhaust passage terminating in a vertically flanged out-

let connection 5 to which is removably clamped the inlet end of a dirt bag 6.

Located immediately forward of the outlet connection 5 from the fan chamber is mounted the cleaner handle 7 having pivotal mounting at its lower end upon an upright supporting bracket 8 secured to the top wall of the exhaust passage from the fan chamber.

The motor 2, as designed for the particular cleaner herein disclosed, is arranged vertically with its armature and field enclosed within a sectional but otherwise solid or imperforate frame 9, except for horizontal slots 9a along either side and a forwardly directed opening at its upper end having the general form of a downwardly and forwardly inclined channel 9b. Also, forming an integral part of the motor casing 9 and extending forwardly over the central portion of the nozzle casing 3 is a block 10 forming the base for a lamp 11 supported upright in a socket 11a positioned just in front of the motor. This lamp, as will later be seen, is intended to illuminate the floor surface immediately ahead of the cleaner, a feature that is quite common in this type of suction cleaner.

However, it may be pointed out at this time that the lamp 11 is enclosed within a separate chamber formed in part by the appearance housing and furthermore, that air for ventilating and cooling the motor enters the motor frame through the slots 9a at its base and is then discharged from the port 9b at the upper end of the motor frame 9, passes through the lamp chamber and thence is discharged downwardly through a group of vertically arranged fan-shaped slots 10a in the lamp base 10 and thence through a discharge passage 12 located immediately below and finally, to the atmosphere through a pair of laterally opening ports 13, 13 just forwardly of the fan chamber, as clearly shown in Figures 1 and 3.

This completes the general cleaner body assembly, except to identify the pairs of front and rear supporting wheels 14, 14 and 15, 15, respectively, the former being journaled at the ends of rearwardly extending horizontal arms 16, 16 formed integral with the rear wall of the nozzle casing 3, as clearly shown in Figure 1, and the rear wheels 15, 15 journaled on a depending bracket 17 fixed to the underside of the fan chamber 1 just forwardly of the flanged outlet connection 5. Also, there is preferably mounted within the nozzle chamber, a rotating agitator or carpet contacting member 18 having operative connection with the motor 2 through a driv-

ing belt 19 and a pulley carried at the lower end of the motor shaft (not shown).

Referring now to the outer appearance housing 20, the same consists of a light shell-like enclosure preferably molded of Bakelite or other plastic substance in one piece and consisting of a lower or body section 20a and a dome-like hood section 20b. The lower section 20a of the housing is relatively shallow with a flat top surface curving downwardly to form skirt-like marginal portions extending in straight lines around the forward portion and curving inwardly along the sides and toward the rear end of the housing.

The dome-like top section 20b follows somewhat the same general contour of the lower section, being somewhat narrower at its rear end than at its forward end. In short, in its general lines the housing inclines toward the so-called stream-lined effect. At the rear end of the dome portion 20b is a U-shaped slot or cut-out portion 21 through which the handle projects as clearly shown in Figure 2, and at the sides and along the base thereof is a pair of slots 22 through which the air enters for ventilating the motor. At the front end of the dome 20b is a window opening 23 preferably closed by means of a transparent panel, this being the window for the lamp 11 mounted immediately behind it.

Now, covering the inner surface of the appearance housing 20 and more particularly the motor enclosing dome portion 20b thereof, is a layer of sound-absorbing material 24, of any suitable substance such as sponge rubber cemented to the surface. This sound-absorbing lining preferably extends throughout the entire inner surface of the housing 20, although it may be confined to definitely prescribed areas. In short, the treatment of the housing for sound reduction would be a matter of determining the limits beyond which little or no additional advantage would be gained by extending the area lined with the sound-absorbing material.

In any case, the appearance housing 20 is fashioned to fit snugly upon and around the body of the cleaner including the nozzle casing 3, as well as the spaces along the sides of the fan chamber including those occupied by the wheels. However, the housing does not extend beyond the flanged outlet connection 5, but terminates in abutting contact with the upper portion thereof, leaving said flanged connection exposed for the attachment of the dirt bag 6.

As a convenient way of anchoring the appearance housing in place after it has been properly seated upon the main body of the cleaner, there is provided on the forward face of the flanged outlet connection 5 a pair of short tapered pins 25, 25, one on either side of the handle supporting bracket 8, as shown in Figure 3. And in the rear wall of the dome portion 20b of the appearance housing is a corresponding pair of holes or sockets adapted to register with these pins and thereby anchor the rear end of the housing securely in place. Finally, screws 26, 26 are inserted through the forward edge of the appearance housing adjacent the outer ends thereof, said screws being anchored in the front wall of the nozzle casing 3, as clearly shown in Figure 1.

In connection with the seating of the appearance housing upon the main frame or the main body of the cleaner, it will be noted that there is provided around the lower edge of the nozzle casing 3 an outwardly extending flange or lip 3a which forms a seat for the lower edge of the corresponding nozzle enclosing portion of the ap-

pearance housing 20, the latter being preferably spaced a short distance from the nozzle casing 3, the intervening space being either filled with the noise reducing lining or left open as the construction may require. And finally, around the lower front edge portion of the housing 20 is a protecting strip of rubber 27 riveted at intervals and forming the usual furniture guard or bumper.

It will be seen that even with the so-called appearance housing removed, the cleaner is fully operative in every respect and particularly in its ability to clean carpets effectively. To be sure, the head lamp 11 would not function effectively for illuminating the floor, and the motor ventilating air would be discharged directly from the top of the motor, but yet the cooling of the motor would not be effected and after all, illumination of the carpet surface in front of the cleaner is not entirely essential for effective cleaning.

In any case, there are definite structural advantages in a design which permits the preliminary assembly of the cleaner as a complete operative device, since it permits a greater latitude in the ornamental treatment of the finished product by making it possible to conceal the entire assembly beneath a housing designed primarily for appearance, although contributing also to quietness of operation by reason of its lining of sound-absorbing material.

Having set forth a preferred embodiment of the invention, but without limiting it to the specific arrangement disclosed, I claim:

3. A suction cleaner comprising a wheeled casing including a fan chamber and a nozzle extending transversely across the front end of said casing and communicating with said fan chamber, a motor mounted upon said casing and driving a fan mounted in said fan chamber, and a one-piece housing of relatively light material adapted to extend over said casing with a portion enclosing said motor and a portion extending laterally and downwardly along the sides of said casing and forwardly and downwardly in contact with the outer surface of said nozzle with its lower edges flush with a marginal flange around the lower edge of said nozzle.

5. A suction cleaner comprising a wheeled casing having a fan chamber and a nozzle extending transversely across the forward end of said casing and communicating with said fan chamber, a motor mounted on said casing for driving a fan in said fan chamber, a handle pivotally mounted on the top side of said casing rearwardly of said motor, and a housing of relatively light material adapted to fit over said casing and having a dome-like central portion enclosing said motor and handle mounting and seating around the base of said motor, skirt-like portions extending laterally and downwardly along the sides of said casing and a nozzle-enclosing portion seating around its lower edge upon an outwardly projecting flange around the base of said nozzle.

3. An ambulatory suction cleaner comprising a body supported on wheels and including a complete fan chamber and a complete nozzle communicating with said fan chamber, a motor mounted on said body and driving a fan in said chamber, said foregoing structure comprising an operative cleaner, a pre-formed rigid contoured housing removably attached to and enclosing said body and embracing the latter to enclose said motor in spaced relation and being contiguous

with a wall of said nozzle, a vertical wall of said housing extending rearwardly from the sides of said nozzle to form skirts which substantially enclose, when viewed from above, the supporting wheels for said body, and sound-absorbing means lining the interior of said housing and disposed adjacent said nozzle wall and spaced from said motor.

4. An ambulatory suction cleaner comprising a body supported on wheels and including a 10 complete fan chamber and a complete nozzle having front and side walls rigidly attached to said body, a complete suction passageway in said

body communicating with said fan chamber, a motor mounted on said body and driving a fan in said chamber, said foregoing structure comprising an operative cleaner, and a pre-formed rigid 5 contoured housing removably attached to and enclosing said body and embracing the latter to enclose said motor in spaced relation and being contiguous with the front and side walls of said nozzle, a vertical wall of said housing extending rearwardly from said nozzle to form skirts which substantially enclose, when viewed from above, the supporting wheels for said body.

FRANK L. PIERCE.
